[57] CLAIM

The ornamental design for an oxygen mask securing straps, as shown and described.

DESCRIPTION

FIG. 1 is a front and left side perspective view of an oxygen mask securing straps showing my new design; FIG. 2 is a top plan view thereof in straightened condition;

FIG. 3 is a side elevational view of FIG. 2, the opposite side elevational view being identical;

FIG. 4 is a front elevational view thereof, the rear elevational view being identical;

FIG. 5 a front and left side perspective view of a second of the oxygen mask securing straps;

FIG. 6 is a side elevational view of FIG. 5 in straightened condition;

FIG. 7 is a front elevational view of FIG. 6;

FIG. 8 is a rear elevational view of FIG. 6;

FIG. 9 is a top plan view of FIG. 6; and,

FIG. 10 is a bottom plan view of FIG. 6.

The portion of FIGS. 1 and 5 shown in broken lines represent an oxygen mask and user and form no part of the claimed design.
